UNITED STATES PATENT OFFICE

2,602,493

COMPOSITE METAL AND WOOD CHAIR
BACK

John S. Burdick, North Muskegon, Mich., assignor to The Shaw-Walker Company, Muskegon, Mich., a corporation of Michigan

Application September 26, 1950, Serial No. 186,811

1 Claim. (Cl. 155—196)

1

This invention relates to improvements in chairs, and more particularly to chairs having certain parts made of tubular metal and other parts made of wood or similar material.

The principal object of the invention is to provide a simple, sturdy and durable construction of the kind above mentioned, which is comfortable and especially attractive in appearance, light in weight and economical in cost of manufacture.

A further object is to provide an improved, simple and efficient means for connecting the wood parts to the tubular metal parts.

Other objects and advantages of the invention will appear from time to time as the following description proceeds.

The invention may best be understood by reference to the accompanying drawing, in which like numerals apply to like parts in each of the figures:

Figure 1 is a top plan view of a chair construction in accordance with my invention;

Figure 2 is a front view of the chair shown in Figure 1, with the chair seat removed;

Figure 3 is a side view of the chair, with the seat in place;

Figure 4 is an enlarged section taken on line 4—4 of Figure 2;

Figure 5 is a section taken on line 5—5 of Figure 4;

Figure 6 is an enlarged detail section taken on line 6—6 of Figure 2, showing a form of support for the upper ends of the back splats;

Figure 7 is a detail section taken on line 7—7 of Figure 6;

Figure 8 is a detail section showing a modified form of support for the upper ends of the back splats;

Figure 9 is a detail section of another modified form of support for the upper ends of the back splats;

Figure 10 is a longitudinal section taken on line 10—10 of Figure 9;

Figure 11 is a detail section showing another modified form of support for the upper ends of the back splats;

Figure 12 is a detail view of another form of support for the back splats, somewhat similar to the modified form of Figure 11;

Figure 13 is a detail section of the top rail of the back frame showing still another modified form of support for the upper ends of the back splats;

Figure 14 is a fragmentary detail perspective view of the top rail, looking from beneath the same, showing a part of the structure of the

2

modified form of back splat support of Figure 13;

Figure 15 is a fragmentary detail perspective view of a cover plate forming part of the modified form of back splat support shown in Figures 13 and 14;

Figure 16 is a detail section showing another form of back splat support;

Figure 17 is a section taken on line 17—17 of Figure 16.

10 Referring now to details of the embodiment of my invention illustrated in Figures 1 to 6, inclusive, the chair shown is of the general type commonly referred to as "visitors' chairs," including as its principal elements a back frame 10, a seat 11, front legs 12, 12, rear legs 13, 13 and arm rests 14, 14. The back frame includes a top rail 15 and upright side rails 16, 16, filled in by a back splat unit indicated generally at 17 including a plurality of upright splats 18 secured at their upper ends to the top rail 15 and at their lower ends to a cross bar 19. The rear legs 13 are prolongations of the side rails 16 of the back frame 10.

15 The seat 11 consists of an open frame 20 made of channel metal construction, on which is mounted a suitable seat member, herein comprising a wooden seat member 21 having its lower margin resting on inwardly turned upper flanged sides of the seat frame 20. Its top surface may be suitably shaped, as usual, to conform to the body of the occupant.

20 The back frame 10 is preferably made of drawn tubular metal construction of generally rectangular cross section. The front legs 12, back splat unit 17 and arm rests 14 are made of wood or similar solid material which, with the wooden seat member 21, lends contrast with the metallic parts, to improve the appearance of the chair. Also, the chair is designed to avoid any bodily discomfort of the occupant by contact with metal parts which tend to give a chilling sensation at relatively low temperatures.

25 Referring now to the means for connecting the ends of certain wooden members to the tubular metal frame members, both the cross bar 19 of the back splat unit and the rear ends of arm rests 14 are connected respectively to the upright side rails 16 of the back frame by similar means, which for convenience will be described in detail as applied to the first-named connection between the cross bar 19 and rail 16, as shown in Figures 4 and 5.

30 An L-shaped bracket 65 has one leg 66 adapted to be attached by screws 67 to the under face of the cross bar 19 adjacent its end, and a second leg

68 adapted to be inserted through a restricted slot 69 formed in the adjacent side wall of the side rail. The slot need only be of sufficient dimensions to permit the leg 68 to be inserted therethrough. The latter leg is then positioned flatwise against the inner face of the adjacent side wall, on the interior of the side rail (see Figure 5). A screw 70 is then passed through said second leg 68 and the adjacent face of the side rail and secured by screwing into the abutting end of the cross bar 19. Access to the screw 70 on the interior of the rail is afforded through a registering hole 71 formed in the outer face of the rail, which hole is normally closed as by a plate 73 with spring retaining prongs 72 on its rear face for holding it in place in said hole.

As will be seen in Figure 5, the lower portion of the leg 68 may preferably be offset or bowed outwardly where it joins the lower leg 66 so as to aid in the insertion of the leg 68 in the restricted slot 69 during the assembly of the parts. It will be understood of course that the preferred procedure of assembly is to insert the leg 68 through the slot 69 first; then engage the leg 68 flatwise in proper position against the inner surface of the wall of the tubular member 16 and apply the screw 70 to the parts, as shown in Figure 4, and finally apply the leg 66 to the under face of the cross bar 19 by screws 67.

Referring to the means for mounting the upper ends of the back splats in the top rail 15, one form is shown in detail in Figures 6 and 7, wherein each splat 18 is inserted through an aperture 80 in the under face of the rail. The upper end of the splat is engaged by spring means mounted within the tubular rail so as to urge said splat toward one lip of the aperture 80. In the form shown in these figures, the spring means comprises a flat or leaf spring 81, bent into generally S shape, with its upper end normally engaged in the upper rear corner of the tubular rail, and its lower end engaged in or adjacent the opposite front lower corner of the tube. When the splat is inserted into place against the tension of the spring, the splat tends to be forced rearwardly so as to be held against the rear lip of the aperture 80. The tension on the spring 81 may be such as to hold the splat against undesirable movements.

In the modified form of splat retaining means shown in Figure 8, the spring 81a is similar to that shown in Figures 6 and 7, excepting that it is in reversed position in the tubular rail, and tends to hold the splat under tension against the front lip of the aperture 80. In this case, the arrangement affords a slight rearward yielding movement of the splat when pressure is exerted thereon by the back of the occupant.

Figures 9 and 10 show another form of splat retaining means wherein the front and rear lips 83 and 84 of the receiving aperture are each bent upwardly in generally parallel relation and are spaced apart so as to receive the splat under slight yielding tension.

The modified forms shown in Figures 11 and 12 are somewhat similar to those shown in Figures 6 and 8, respectively, excepting that the leaf springs 85 and 86 are each generally of the shape of the numeral 6, and are arranged with their doubled spring portions in mutually reversed positions at the front and rear, respectively, of the splat.

Figures 13, 14 and 15 show still another form of splat retaining means, which is similar in principle to the form shown in Figures 9 and 10, excepting that in this case the opposed yielding lips 87, 88 are formed on a separate plate 89 which is suitably fixed to the under face of the top rail 15, with the several lips 87, 88 projecting into an elongated slot 90 formed along the bottom of top rail 15.

Figures 16 and 17 show another variant of splat retaining means, wherein a coil spring 92 is mounted along one corner, herein the front upper corner, of the interior of the tubular rail, in position to be partially compressed when the splat is inserted in said rail, as indicated in dotted lines in Figure 16.

Although I have shown and described certain embodiments of my invention, as applied to a back rest made up of back splats, and a horizontal cross bar, it will be understood that the same connecting means between the back rest and the chair frame can equally well be employed with other types of back rest means such as wood, metal, plastic or upholstered back rest units including spaced, vertical or horizontal frame members connected to the metal chair frame. Therefore, I do not wish to be limited to the exact constructions shown and described, but that various changes and modifications may be made without departing from the spirit and scope of the invention as defined in the appended claim.

I claim:

In a composite metal and wood furniture structure, a tubular metal frame member and a wooden member adapted to be connected to said frame member in generally endwise abutting relation, said tubular frame having a slot-like aperture therein and a metal bracket bent in angular form, with one generally flat leg adapted to be passed through said slot-like aperture in the wall of said tubular frame and swung into engagement flatwise against the inner face of said frame member with another leg of said bracket extending from said aperture and secured along one side of said wooden member, screw means passing through said first-named leg, the wall of said tubular member and into the abutting end of said wooden member, said tubular member also having an aperture in the wall opposite said slotted aperture to afford access to said screw means.

JOHN S. BURDICK.
